Attorney

UNITED STATES PATENT OFFICE.

JOHN CESSNA, OF LOCUST GROVE, OHIO.

ANCHOR FOR WIRE-STRETCHERS.

1,211,084.

Specification of Letters Patent.

Patented Jan. 2, 1917.

Application filed April 21, 1916. Serial No. 92,776.

To all whom it may concern:

Be it known that I, JOHN CESSNA, a citizen of the United States, and resident of Locust Grove, in the county of Adams and State of Ohio, have invented certain new and useful Improvements in Anchors for Wire-Stretchers, of which the following is a specification.

The present invention relates to new and useful improvements in anchoring device for fence stretchers and the like and the primary object of my invention is to provide an anchoring device capable of detachable association with a fence post or the like to serve as an anchor for one end of any conventional form of wire stretching device.

Another object of my invention is to provide an anchoring device of the class described having improved bracing means associated therewith.

A further object of my invention is to provide an anchoring device of the class described having improved means for bracing the same against a fence post, the other bracing means hereinbefore mentioned serving to prevent lateral displacement of the anchoring device during a stretching operation.

Other objects and advantages to be derived from the use of my improved anchor for wire stretchers will appear from the following detail description and the claim, taken with an inspection of the accompanying drawings, in which;

Figure 1 is a perspective view of an anchoring device embodying the improvements of my invention, the same being shown in operative position; Fig. 2 is a fragmental perspective view of one end of one of the bracing arms of the anchor and a connection associated therewith; Fig. 3 is an enlarged fragmentary elevational view of the anchoring device and connection of the same with the braces; Fig. 4 is a fragmental perspective view of one end of one of the post engaging elements; and Fig. 5 is an enlarged fragmentary transverse sectional view of the connecting means between the anchor and one of the post engaging arms.

Referring more particularly to the drawings, wherein similar characters of reference designate like and corresponding parts throughout the various views, 1 designates the main body portion of my improved anchoring device the lower free end thereof

being adapted to engage the earth as best shown in Fig. 1.

The anchoring device 1 is maintained in vertical position by means of angularly extending braces 2 having U-shaped looped members 3 carried on the free extremities thereof, said members 3 being engaged by staples 4 carried by the body 1, this structure being best shown in Fig. 3. It will be seen that the structure of the connecting means between the braces and the body 1 serves as a semi-universal connection permitting the braces 2 to engage the earth as best shown in Fig. 1 at the proper bracing angle. It is to be understood, of course, that the anchor and its braces do not penetrate the earth to any great extent but may rest merely upon the surface.

I have shown a fence post designated 5, said post being of the usual type, a wire fence structure being designated 6 and having the free end thereof engaged by clamping jaws 7 of a conventional form of wire stretcher, said jaws 7 being connected by a cable 8 with a wire stretcher 9 of the bar type, a second cable 10 connecting at 11 with the anchor 1 affording means against which the stretcher may operate.

I provide post engaging elements, one of the elements being adapted to positively engage a post the other element being adapted to impinge against the post. Said post engaging elements include arms 12 and 13 connected as at 14 with the body 1, a suitable connection, the preferred form of which is hereinafter described, being provided therefor.

The arm 12 is adapted to impinge upon the post 5, said arm having an arcuate end portion covered by a metal plate 15, through which projects a prong 16, said prong being located approximately centrally of the curved portion of said arm. The foregoing structure is best shown in Fig. 4.

The arm 13 is provided with means for bracing the fence post 5, said means including a U-shaped strap 17 having the arms 18 thereof provided with notches 19 in the upper marginal edges. The arms are adapted to project through loops 20 carried by opposite faces of the arms 13 and the notches 19 are adapted to engage pins 21 carried by said arm 13. This arrangement permits adjustment of the strap 17 into clamping engagement with the post as best shown in Fig. 5.

Fig. 1. However, the structure *per se*, as described, is best shown in Fig. 2.

The connecting means hereinbefore broadly designated 14 in Fig. 1 is best shown in detail in Fig. 5. Both of the connecting means mentioned are identical therefore a brief description of one will suffice. Referring to Fig. 5 I provide a U-shaped member having a lateral portion 22 and parallel extending arms 23, the free ends of said arms being sharpened and bent inwardly to engage the arm, in the present instance the arm 12 as indicated at 24. Staples 25 engage the arms 23 and prevent dislodgment of the same from the post engaging member.

The arm 12 is provided with a recess 26 approximately centrally of the end face of the arm and adapted to receive a U-shaped staple or the like 27 carried by the anchor portion 1. The anchor portion 1 is provided with a similar recess 28 adapted to receive a lateral portion 22 of the connecting member carried by the post engaging arm 12.

In use it will be seen that the body portion 25 of the anchor is placed upon the earth in alinement with the fence line and the arms 12 and 13 are engaged as shown in Fig. 1 with the post. The braces 2 are now placed at the proper angle and engage the earth, it being shown that the lower ends of said arms are beveled. By attaching the wire stretcher as shown the fence structure 6 may be drawn to the position desired. Of course, it will be understood that while I have shown my invention applied as an anchor for wire stretchers it is not desired that I be limited to this application of my invention. It will be seen that owing to the semi-universal joint between the post engaging

arm and the anchor body and the similar engagement between said body and the braces permit folding of the device to a comparatively small space of packing and shipment. 40

From the above description taken in connection with the accompanying drawing, it 45 is thought that a clear and comprehensive understanding of the construction, operation and advantages of my invention may be had, and while I have shown and described my invention as embodying a specific structure, I desire that it be understood that I 50 may make such changes in said structure as do not depart from the spirit and scope of the invention as claimed.

Having thus fully described my invention, 55 what I claim as new and desire to secure by Letters Patent, is:—

A wire stretcher anchor comprising a vertical standard, post engaging arms connected to the standard, said connection including a U-shaped member, the ends of said member being bent into engagement with the arm, staples engaging the U-shaped member and the arms to prevent dislodgment of the same, the end of the arm being 60 provided with a recess intermediate the edges thereof, said recess being adapted to receive a U-shaped staple attached to the standard and embodying the first mentioned U-shaped member, and the said standard 65 being provided with a recess to receive the end of the first mentioned U-shaped member, and brace arms carried by said standard universally connected therewith for a purpose 70 specified. 75

In testimony whereof, I affix my signature hereto.

JOHN CESSNA.
